CLAIM

We claim the ornamental design for a pistol handgrip, as shown and described.

DESCRIPTION

FIG. 1 is a perspective view of a pistol handgrip according to the present invention;

FIG. 2 is a left side view of the pistol handgrip;

FIG. 3 is a right side view of the pistol handgrip;

FIG. 4 is a front view of the pistol handgrip;

FIG. 5 is a rear view of the pistol handgrip;

FIG. 6 is a top view of the pistol handgrip; and,

FIG. 7 is a bottom view of the pistol handgrip.

The portions of the pistol handgrip shown in broken lines are included for the purpose of illustrating environment and form no part of the claimed design.
